UNITED STATES PATENT OFFICE.

ALBERT HOMER CANFIELD, OF BRIDGEPORT, CONNECTICUT.

METHOD OF PRODUCING TANK BALLS.

Application filed November 2, 1922. Serial No. 598,593.

To all whom it may concern:

Be it known that I ALBERT H. CANFIELD, a citizen of the United States, residing at Bridgeport, in the county of Fairfield and 5 State of Connecticut, have invented certain new and useful Improvements in Methods of Producing Tank Balls, of which the following is a specification.

This invention pertains to an improved 10 method of producing tank balls and has for its main object the production of a superior ball without seams or joints and this in what may be termed a single step process.

The apparatus whereby the method may 15 be carried out, as well as various forms of balls falling within my invention, are illustrated in the annexed drawings, wherein,—

Fig. 1 is a sectional elevation of the upper portion of the mold, the core or spreader 20 being shown in full;

Fig. 2 a sectional view of the lower portion of the mold, the spud and the sheet of material which forms the outer relatively hard or stiff face of the upper portion of 25 the finished ball being shown in section, while the mass, from which the body of the ball is formed, is shown in full;

Fig. 3 is a sectional elevation of the mold section assembled, with the molded ball 30 likewise shown in section;

Fig. 4 a sectional elevation of the completed ball;

Fig. 5 a sectional view of the upper section of the mold, with the core piece 35 moved;

Fig. 6 a face view thereof, looking down into the mold cavity;

Fig. 7 a perspective view of the core 40 piece;

Fig. 8 a sectional view of the lower mold member;

Fig. 9 a face view thereof looking into the mold cavity;

Fig. 10 a detail sectional view illustrating a modified manner of positioning the spud; and

Fig. 11 a sectional elevation of a slightly modified form of ball.

Referring first to Figs. 1 to 9, inclusive, 50 1 denotes the upper mold member provided, as is usual, with a plurality of guide pins 2 adapted to pass into openings 3 formed in the lower mold section or member 4 to effect proper registry of the mold members

when they are moved toward each other to 55 closed position in the act of shaping and producing the ball. It is to be understood that the terms upper and lower, as applied to the mold sections, are merely relative and is employed merely as a matter of convenience, as their position might be reversed, though the operation of placement of the materials and parts could not be so conveniently effected as when the parts are used in the relation shown and described. 60 65

The upper member 1 is provided, in its under side, with a cavity 5 substantially semi-spherical in form, the upper portion of the curvature being interrupted, however, by an inwardly projecting portion 6, 70 presenting a flat inner face 7 and producing a shoulder 8. A round opening 9, formed coaxial with the cavity 5 and projection 6, extends through the mold section, and is designed to receive the stem 10 of 75 the core piece, shown in Figs. 1, 3 and 7. Said core piece has the form which it is desired to impart to the interior of the ball, and may be said to comprise a frusto-conical section 11, and a rounded section 12, 80 substantially hemi-spherical in contour, and formed upon a radius somewhat smaller than that of the mold cavity 5. The upper portion of the core is formed with a flat face 13 and a land or shoulder 14, the diameter of the former being the same as that of the flat face 7.

When the core is positioned in the mold section 1 the stem 10 passes into the opening 9 and the flat face 13 abuts the face 7 90 on the mold section. With the parts thus positioned there is formed between the hemi-spherical portion 12 of the core and the adjacent wall of the cavity 5, a space or chamber, denoted by 15, which, at its 95 upper end, is somewhat enlarged, as at 16, (see Fig. 1).

The lower mold section 4 is provided with an inverted frusto-conical cavity 17, from the bottom of which there extends 100 upwardly a pin 18 adapted to receive and position the usual spud 19 employed in tank bulbs. The pitch of the cone shaped cavity 17 is somewhat more obtuse than is that of the cone shaped section 11 of the core, so that when said core element extends down into the cavity 17 the walls of the two elements do not stand in parallelism, thereby 105

producing a space between the walls of increasing measurement toward the bottom of the cavity or toward the spud.

It is conceivable, of course, that the same grade and character of stock throughout may be employed to produce a ball with the mold as above described, but I prefer to produce a ball having its head or upper portion relatively hard as compared to the lower or seating portion. To this end, after having placed the spud 19 upon the pin 18, I impose thereover and thumb down within the cavity 17, a sheet or disk of rubber 20, (Fig. 2) so compounded that when vulcanized it becomes relatively hard or stiff. If desired, the disk which is preferably formed with a central aperture 21 may be forced down and around the spud so as to engage the same, but so far as actual results are concerned, this is immaterial. I next place upon the sheet or disk 20 a cylindrically shaped block of relatively soft curing rubber, denoted by 22, and when this is done the two mold sections which are hot, to a greater or less degree, are brought together. The lower end 11 of the core contacts the block 22, and causes the same to flow laterally, and likewise to force disk 20 downwardly around the spud and into close and intimate contact with the wall of cavity 17. At the same time the material in block or mass 22 passes up along the face of the cone shaped element 11 of the core, and finally flows into and fills the space or chamber 15 and the enlarged annular space 16. The disk and block will be so proportioned as to mass as to fully fill all the mold cavities, and should there be any excess, it will be extruded outwardly between the abutting faces of the mold sections. The mold is then clamped and subjected to such a degree of heat as will properly vulcanize the rubber stock. When vulcanization has been effected the mold sections are separated, and by reason of the core being embraced within the ball, the latter will be withdrawn from the cavity 17, and carrying with it the embedded spud. The core is then knocked from the mold section 1 by tapping upon the outer end of pin 10, and this leaves the finished ball, comprising the upper frusto-conical section 23, and the lower substantially hemi-spherical valve seat contacting section 24, upon the core. It may be readily removed therefrom by the operator. He preferably passes a pin through a hole 25, formed in the stem 10, to afford a proper hold upon the core, and thereafter loosens the section 24 by running a tool inwardly and around between said section and the core, whereupon by grasping the ball and turning the core therein, the ball may be peeled off, as it were, from the core. The opening 26 in the end of the relatively soft and yielding section 24 may be stretched

enough to allow of such removal of the core. It will be noted that the margin of opening 26 is defined by an interior rib 27, which is formed in the enlarged annular space or chamber 16, and this rib or enlargement prevents the ball from being torn when removed from the core, and likewise stiffens the same against collapse.

It will also be noted, upon reference to Figs. 3 and 4, that the soft rubber body of the upper section of the ball, is thicker toward the spud end than it is at the other portions. In other words, by reason of the difference in angularity between the cavity 17 and the frusto-conical section 11 of the core, the upper portion of such soft rubber body or that which lies within the hard outer facing, is relatively thick, or increases in thickness toward the spud.

Inasmuch as the ball is produced in a single heat and there is no preforming or pre-molding of separate sections or halves, requiring subsequent joining with a consequent seam, the method is at once simple and effective. The material in the block or charge 22 is coextensive of the upper and lower portions of the ball, and this without the presence of any seams or joints. The outer upper end facing formed from the disk 20 becomes amalgamated with the underlying material, and, in practice, unless different colored stock is employed in the disk and charge 22, the line of juncture is imperceptible.

In Fig. 10 a slightly modified manner of mounting the spud is shown. In this instance, the spud 19 has threaded into it a short pin or stem 28, which passes freely down through an opening formed in the bottom section of the mold, the free fit allowing for the venting of the air.

In Fig. 11 a slightly modified formation of the tank bulb is illustrated, wherein a layer of fabric, denoted by 29, is shown as lying between and embedded in the adjacent faces or portions of the inner relatively soft rubber and the harder outer facing body. This may be readily embodied in the structure by imposing a piece of frictioned fabric upon the disk 20 before the body charge 22 is placed thereon. The presence of this fabric may be found advantageous in tank balls of the larger sizes.

While it is preferred to employ a core piece produced as an integral structure, it is to be understood that in practicing the method as herein set forth, a multi-part core may be employed.

No claim is made herein to the tank ball as such, the same being divided out of this application pursuant to the requirement of division made by the Patent Office. The claims directed to the article or ball form the basis of my divisional application filed on or about March 24, 1925, Serial No. 18,013.

What is claimed is,—

1. That method of forming tank balls which consists in placing within a cavity formed in a mold section, material sufficient to produce the ball in its entirety forcing down onto said material a second mold section, said second section having a core mounted in a cavity formed therein and in spaced relation to the walls of the cavity, said core likewise having an outwardly extending portion which portion when the mold sections are brought together contacts the material and causes a flow thereof throughout the cavities in the mold and finally vulcanizing the ball thus produced. 15
2. That method of forming tank balls which consists in placing within a cavity formed in a mold section, material sufficient to produce the ball in its entirety and forcing down onto said material a second mold section, said second section having a core mounted in a cavity formed therein and in spaced relation to the walls of the cavity, said core likewise having an outwardly extending portion which portion when the mold sections are brought together contacts the material and causes a flow thereof throughout the cavities in the mold, 25 and finally vulcanizing the ball thus produced.
3. That method of producing tank balls having a relatively stiff upper portion and a softer seating portion, which consists in placing a disk or sheet of hard curing rubber within a cavity formed in a mold section; placing on the disk a body of soft curing rubber in a quantity sufficient to be coextensive of the upper and lower portions 35 of the ball, thereafter pressing a second mold section against the other, said second mold section carrying a core which causes the material to flow into and fill the cavities formed between it and the walls of the cavities in the mold sections and finally vulcanizing the ball thus produced. 45
4. That method of producing tank balls, which consists in placing a body of relatively hard curing stock in a female mold, 50 imposing thereon a body of relatively soft curing stock, bringing a male mold, sur-
- rounded by a stock receiving cavity, into pressing relation to the stock and finally vulcanizing the ball thus produced. 55
5. That method of producing tank balls, which comprises the imposing of a body of soft curing rubber upon a sheet of hard curing rubber and subjecting the same to molding pressure and heat within a mold structure sufficient to cause the soft rubber 60 to flow into and throughout the mold cavity and simultaneously produce a conforming of the sheet to the adjacent wall of the mold and a coalescence thereof with the soft body. 65
6. That method of producing tank balls having a relatively stiff top with a spud embedded therein, which comprises positioning a stud within a mold; placing a sheet of relatively hard curing rubber 70 thereover, said sheet being of such size as to be coextensive of the upper outer face of the finished ball; imposing a body of soft curing rubber on the sheet, said body being of sufficient volume as 75 to produce the lower soft portion of the ball and an inner covering or lining for the upper portion of the ball; subjecting the sheet and body to molding pressure and heat within a mold structure sufficient to cause the soft rubber to flow into and throughout the mold cavity, and simultaneously produce a conforming of the sheet to the adjacent wall of the mold and a coalescence thereof with the soft body and finally vulcanizing the ball thus produced. 80
7. That method of producing tank balls, having a relatively stiff top, which consists in lining or facing a cavity formed within a half mold section with a sheet of relatively hard curing rubber; imposing a body of soft curing rubber on the sheet thus positioned; and finally bringing a core, carried by a second half-mold section and held in spaced relation thereto, against said body and thereby causing, as the mold sections are closed, a flow of the rubber body over the sheet and into and throughout the mold cavities. 85

In testimony whereof I have signed my name to this specification.

ALBERT HOMER CANFIELD.
